MONEY DRAWER AND SAFETY LOCKER

Albert L. Abbott and William C. Miller, Canton,
Ohio, assignors to Diebold Safe & Lock Co.,
Canton, Ohio, a corporation of Ohio

Application September 9, 1933, Serial No. 688,857

17 Claims. (Cl. 70—62)

This invention relates to a money drawer and safety locker of a type adapted to be installed in tellers' cages of banks, etc.

An object of the invention is to provide an improved drawer and locker construction which may be quickly or automatically closed and locked to protect funds in the drawer and locker, in the event of an attempted robbery. A further object is to provide improved electrically operated means for quickly closing the money drawer and locking it and the locker for a predetermined period. Other specific objects and advantages will appear as the specification proceeds.

The improved construction consists broadly of a money drawer withdrawably mounted above a locker chest with a communicating passage between the drawer and chest, power means for quickly moving the drawer into closed and locked position, auxiliary locking means on the locker, and mechanism for maintaining the drawer lock and auxiliary lock in operative locking position until a predetermined time has elapsed, and then freeing the drawer and the auxiliary lock. The invention contemplates the use of a plurality or battery of drawers and lockers, as well as the single drawer and locker construction described.

The invention is illustrated, in its preferred embodiment, by the accompanying drawings, in which—

30 Fig. 1 is a front view in elevation of a drawer and locker embodying my invention; Fig. 2, a broken side view in elevation; Fig. 3, a broken plan sectional view, the section being taken as indicated at line 3—3 of Fig. 1, and the drawer being shown in withdrawn position; Fig. 4, a vertical sectional view, the section being taken as indicated at line 4—4 of Fig. 1; Fig. 5, a broken sectional detail view, the section being taken as indicated at line 5—5 of Fig. 1; Fig. 6, a broken sectional detail view, the section being taken as indicated at line 6—6 of Fig. 5; Fig. 7, a broken plan sectional view, the section being taken as indicated at line 7—7 of Fig. 1; Fig. 8, a sectional detail view of contact members leading to the auxiliary lock of the safety locker; Fig. 9, a broken enlarged detail view of a portion of the rotatable retarding rod; Fig. 10, a detail sectional view, the section being taken as indicated at line 10—10 of Fig. 3; Fig. 11, a broken plan view of a portion of the money drawer showing the locking mechanism therefor; Fig. 12, a sectional view, the section being taken as indicated at line 12—12 of Fig. 11; Fig. 13, a transverse sectional view, the section being taken as indicated at line 13—13 of Fig. 11; Fig. 14, a rear view in elevation of the

locker door, the rear wall of the locker having been broken away to expose the lock mechanism; Fig. 15, a transverse sectional view, the section being taken as indicated at line 15—15 of Fig. 14; Fig. 16, a sectional view, the section being taken as indicated at line 16—16 of Fig. 14; and Fig. 17, a schematic view of the wiring layout.

In the illustration given, A designates a casing; B, a money drawer mounted in the upper part of the casing, and C, a locker below the 10 money drawer.

The casing A may be of any suitable construction. In the illustration given, it comprises a rectangular chest having an open front end, the open end being closed by the front wall 10 of 15 drawer B and the door 11 of locker C. The door 11 is secured by hinges 12 to one side wall of casing A.

The casing A is provided with a horizontal partition wall 13 separating the drawer compartment from the locker compartment, and supported upon the partition 13 adjacent the side walls are roller tracks 13^a in which are mounted rollers 14. In view of the well known construction of the roller track, a detailed description is 25 believed unnecessary.

The drawer B may be of any suitable construction. In the illustration given, it is provided with a front wall 16 adapted to close the drawer compartment and with bottom and side walls and 30 with a plurality of compartment walls 15 dividing the drawer into a number of money tills. In the rear left hand corner, there is provided a compartment 16 having a hinged or trap door bottom 17. The trap door is adapted to swing 35 through an opening 13^b in the partition wall 13 when the door 17 becomes aligned therewith, as shown more clearly in Fig. 5. A centrally disposed guide track 18 is supported so as to engage the central portion of door 17 and maintain it 40 closed when the drawer is in open position. Near its rear end, the track 18 is inclined downwardly at 18^a, and rollers 18^b are mounted in the section 13^a to facilitate the lowering and raising of trap door 17. The drawer B is supported on the 45 rollers 14 by the flange extensions 19, as shown more clearly in Fig. 6.

Any suitable means may be employed for locking the drawer. As shown more clearly in Fig. 11, a key-controlled spindle 20 is equipped with a 50 bar 21 to the ends of which are secured draw-arms 22. The arms 22 extend through openings in the side walls of the drawer and engage front walls A' of the casing A. The turning of the spindle 20 by the key causes the bar 21 to swing 55

in a rotary movement and moves the locking rods 22 to closed or open position. A handle 23 is provided for the drawer B.

The locker C may also be of any suitable construction. As shown more clearly in Figs. 4 and 7, the locker compartment is provided on one side with a partition wall 24 providing a compartment for the batteries, switches and other mechanism which will be described hereinafter. A floor 25 for the locker compartment is provided a short distance above the bottom wall of the locker and provides a wiring compartment 25^a immediately below the floor 25.

Any suitable locking mechanism may be provided for the locker door 11. In the illustration given, the door is provided with a rotary disk 26 provided on opposite sides with locking teeth 26^a and 26^b. Pivotally connected to opposite sides of the disk are locking bolts 27 equipped with springs 27^a. A combination lock 28 controls a bolt 28^a adapted to engage the projection 26^a on disk 26 to prevent rotation of the disk. An auxiliary lock 29 engages the tooth 26^b of disk 26, and serves also to prevent rotation of disk 26. The auxiliary locking bolt 29 is controlled by a solenoid 30 equipped with wires leading to contact members 31. A handle-equipped shaft 32 is connected to locking disk 26 and extends through the front wall of the door C.

Our invention includes the use of mechanism which, when actuated, quickly and silently closes the drawer and locks the drawer in closed position until a predetermined time has elapsed. The specific mechanism illustrated for this purpose will now be described. The mechanism is preferably mounted in the space between drawer B and the horizontal partition 13, and at the rear of drawer B. A guide rod 33 and a retarding rod 34 are supported by brackets 35 and 35^a longitudinally of the compartment and provide a track for the carriage member 36. Secured to the carriage is a flexible strap 37 which is wound upon a drum 38. The drum 38 is mounted upon shaft 38^a rotatably supported in bracket members 38^b. A coil or power spring is secured to one end of the shaft 38^a and housed within casing 39. Also secured to shaft 38^a is a ratchet wheel 40. Adjacent the wheel 40 is a spring-held pawl 41 adapted to be actuated by solenoid 42. A spring member 43 serves to urge the pawl out of contact with ratchet wheel 40.

The retarding rod 34 extends through the supporting bracket 35, and is supported by bracket 34^a. As shown more clearly in Fig. 9, the rod 34 is provided at its rear with an enlarged end 44, and fixed thereto is a reduced extension 44^a which extends into a recess of end member 45. The member 45 is threaded at its outer end and engaged by nut 46. Between the members 44 and 45, is a leather washer 47. With the arrangement shown, the friction on rotatable rod 34 may be increased or diminished according to the adjustment of nut 46. The rotatable rod 34 is provided with a spiral groove 48 adapted to be engaged by a finger 49 carried by carriage 36. The rotation of the rod, as the carriage moves rearwardly, causes the drawer to move silently and with reduced speed to closed position.

The carriage member 36 is provided with an upwardly extending rear wall adapted to engage a downwardly turned flange 50 secured to the drawer B. As the carriage moves inwardly, it strikes the flange 50 on the drawer, and causes the drawer to be carried to the inner position.

In order to render the drawer-retracting mech-

anism inoperative except when an emergency exists, we provide a catch construction which engages the carriage 36 and maintains it in forward position until an actuating button is pressed. In the illustration given, a latch member 51 is pivotally secured at 51^a, and is provided with a catch 51^b engaging the front wall 36^a of the carriage. Secured to an outer arm of the latch member 51 is a rod 52. The rod is secured to one end of the pivoted bar 53 which is urged upwardly by spring member 56. The bar 53 is normally held in the position shown in Fig. 3, above the breaker switch 54, by a pivoted trigger 55 which engages a recess 53^a in the bar 53. The spring 56 engages the members 53 and 55 and tends to urge them toward the position shown in Fig. 3. The spring breaker switch 54 is normally held closed by engagement with member 53, as shown in Fig. 3, but opens to break the circuit after member 53 has been tripped, thus stopping the further flow of current to solenoid 58. A plunger 57 is slidably mounted within solenoid 58 and adapted to be urged forward thereby when the solenoid is energized, to push the upper end of trigger 55 in a forward direction. This movement releases the bar 53 which is urged upwardly by spring 56 so as to depress rod 52, thus freeing catch 51 from its interlocking connection with carriage 36.

Solenoid 30 controlling the auxiliary lock 29 is connected so as to be actuated at the same time that solenoids 58 and 42 are energized. For the sake of clearness in the drawings, the wires connecting the various parts are omitted, but the connections are clearly shown in the wiring layout in Fig. 17, which will be later described. The contact members 31 on the locker door C are adapted to be brought against the fixed contact members 59, as shown in Figs. 7 and 8. The contact members 59 are supported by wall 24 which forms with the casing in the lower compartment of the safe, a battery compartment 24^a. Within compartment 24^a are arranged dry cells 60. The battery is connected, as shown in the wiring layout, with a dash-pot relay 61, a make-and-break relay 62, and with a reset switch 63. From compartment 24^a, lead wires 68 and 75 pass downwardly through the bottom of the compartment into the narrow wiring compartment 25^a.

Referring more specifically to the wiring layout in Fig. 17, it will be observed that a closed circuit is employed. A wire 68 leads from the make-and-break relay 62 to a series of switches 67. It will be understood that the switches may be located at any convenient point in the bank or other building. A line 71 joins the switches at the other end with contact member 72. The relay 62 actuates armature 73 which, by means of links, tends to swing the switch arm 71 into contact with contact arm 72. When the magnet 62 is released, the arm 71 falls into engagement with contact arm 73. Line 74 leads from the contact point 73 to the dash-pot relay 61. From the switch 71 line 76 leads to a vertical line 77 connecting with battery 60 on one side and with 65 the reset button 63 on the other side. Line 78 leads from battery 60 to the solenoid 42. Line 79 leads from line 69 to solenoid 30 on the safe door and return line 80 connects solenoid 30 with line 74. The solenoids 42 and 58 are connected in parallel by lines 81 and 82, the line 82 joining line 83 which connects solenoid 42 to line 74. Adjacent the dash-pot relay 61 is an armature 84 which, when actuated, moves switch 85 into engagement with contact point 86. The contact 75

point 86 is connected to line 77, while switch 85 is connected to line 87. Line 87 extends between the reset switch 63 and contact point 72.

In operation, the current flows normally from battery 60 through line 78, the coil of relay 62, energizing same, through line 68, switches or circuit closing devices 67, thence returning through line 75, contacts 72 and 71, and through lines 76 and 77, back to battery 60. Under this normal operation, no current flows through any of the other devices.

Opening any part of the circuit between lines 68 and 75, as by manipulating one of the switches 67, deenergizes the make-and-break relay 62, allowing a contact to be set up between contacts 71 and 73. The current then flows from battery 60, through line 78, ratchet magnet 42, line 83, line 74, contact points 73 and 71, and then through 76 and 77 back to battery 60. The release magnet 58, being connected in multiples through lines 81 and 82, and through lines 78 and 83, leading to ratchet magnet 42, become energized at the same time as solenoid 42 is energized, but as soon as the release magnet functions, it opens switch 54, thus stopping the current flow and releasing magnet 58.

The door magnet 38 is also multiple-connected through lines 78 and 80 and lines 69 and 74 and it is energized at the same time as release magnets 42 and 58.

Also connected in multiples to the magnets 38, 42 and 58, is the time delay solenoid 61. The energizing of the coils of the solenoids causes, after a predetermined time, contacts 85 and 86 to close. These contacts shunt contacts 71 and 72 of the make-and-break relay so that a current (providing the circuit containing the circuit opening device has been put in order) is set up in the make-and-break relay energizing coil and causes a break between 71 and 73, thus releasing the various locking magnets and restoring a normal circuit through contacts 71 and 72.

The push button 63 is provided so that the restoration of current through the make-and-break relay can be established without waiting for the action of the time delay solenoid. Thus, while the mechanism is being repaired and the door is open, the button 63 may be pressed to release the latch members without requiring the mechanic to wait until the time mechanism has run.

Referring to the mechanical parts, the operation is as follows: In the ordinary or everyday use of the money drawer, the operator closes and opens the drawer just as the ordinary drawer is opened and closed. The locking bolts 22 are manipulated by the turning of the key stem 20 by the teller's key. In the event of an attempted robbery, the button, which is near the teller or near some officer of the bank, is pressed so as to energize the solenoids 58, 42 and 30. As the solenoid 58 is energized, plunger 57 is pushed forward against trigger 55 to release the pivoted member 53. The spring 56 then urges the free end of lever 53 upwardly and depresses rod 52. Rod 52, in turn, releases catch 51 from interlocking connection with the carriage 36. The carriage is drawn rearwardly by strap 37 connected to drum 38 and carried by shaft 38a. The power is supplied by the wound coil spring in casing 39. The rearward movement of carriage 36 is slightly retarded and rendered noiseless by the engagement of finger 49 with the spiral groove 48 of the rotatable rod 34, friction being supplied to the rod 34 by means of washer 47 and adjustable nut 46. The rearward movement of carriage 36

brings its vertical extension 36a into contact with the depending flange 50 which is fixed to drawer B. Drawer B is thereby retracted with the carriage into the drawer compartment. The energizing of solenoid 42 causes the pawl 41 to be drawn forward into contact with ratchet 40. However, as the ratchet revolves with shaft 38a during the closing of the drawer, the teeth slip over the pawl 41. When the drawer has been closed, the engagement of pawl 41 with the ratchet 40 prevents counter-movement of shaft 38a, and locks the drawer against withdrawal. At the same time, the solenoid 30 on the door of the locker is energized and forces the auxiliary locking bolt 29 forward to engage the lug 26b of lock-disk 26. Rotation of the locking disk is thus prevented until the solenoid has been released.

Release of the auxiliary lock 29 and of the pawl 41 is effected after the dash-pot has operated for a predetermined period, as has been described. Instead of a dash-pot, it will be understood that other timing mechanism may be employed to effect release of the locked parts. After the solenoids have been de-energized, the drawer B may be withdrawn, and the door of the locker 25 may be unlocked by simply manipulating the combination 28. In the withdrawal of the drawer, however, the safety apparatus is reset, the flange 50 of the drawer engaging flange 36a of the carriage and drawing strip 27 to the extended position shown in Fig. 3. This movement serves to wind the spring in casing 39, and at the same time, catch 51 snaps into locking engagement with carriage 36, and the parts 53 and 55 assume their position shown in Fig. 3.

While we have described the mechanism as being electrically operated by current supplied from dry cells, it will be obvious that current may come from an external source; also, it will be obvious that mechanical timing and other mechanism may be employed for the automatic locking and unlocking operations.

In the construction illustrated, we have shown the timing release mechanism housed within the unit. It will be obvious that the release may be effected positively upon the manipulation of a switch outside of the unit. For example, the switch might be located in a safe controlled by time-lock mechanism of the type shown in Miller and Kuenzel application, Serial No. 613,954, or by other suitable delayed time-lock mechanism.

The foregoing detailed description has been given for clearness of understanding only, and no unnecessary limitations should be understood therefrom, but the appended claims should be construed as broadly as permissible, in view of the prior art.

We claim:

1. In apparatus of the character set forth, a casing providing a drawer compartment, a drawer 60 slidably mounted therein, power means within said casing for closing said drawer, means associated with said drawer for automatically charging said power means when the drawer is withdrawn, means outside of said drawer for actuating said power means to close the drawer, and rotatable friction means for retarding the closing of the drawer.

2. In apparatus of the character set forth, a casing providing a drawer compartment, a drawer 70 withdrawably mounted in said compartment, power means of variable intensity within said casing for closing said drawer, a rotatable rod member provided with a spiral groove associated with said power means, means carried by said

drawer and engaging said groove to rotate said rod for cushioning the closing movement of said drawer, and means for actuating said power means.

5. 3. In apparatus of the character set forth, a casing providing a drawer compartment, a drawer slidably mounted therein, a carriage member provided with an interlocking member adapted to engage a member carried by said drawer, 10 means slidably supporting said carriage member longitudinally of said compartment, power means associated with said carriage for withdrawing said carriage toward the rear wall of said compartment, locking means for preventing withdrawal of said drawer, and means for cushioning and retarding the closing movement of said drawer.

4. In apparatus of the character set forth, a casing providing a drawer compartment, a drawer slidably mounted therein, a track running longitudinally of said compartment, a carriage on said track, interlocking elements carried by said carriage and said drawer, a flexible strap member secured to said carriage and to a rotatably mounted drum, spring power means for rotating said drum, latch means maintaining said carriage in forward position against the tension of said spring, release means adapted to be actuated to release said latch means, locking means adapted to prevent withdrawal of said drawer, and means for releasing said locking means after a predetermined time.

5. In apparatus of the character set forth, a casing providing a drawer compartment, a drawer slidably mounted therein, a track running longitudinally of said compartment, a carriage on said track, interlocking elements carried by said carriage and said drawer, a flexible strap member secured to said carriage and to a rotatably mounted drum, spring power means for rotating said drum, latch means maintaining said carriage in forward position against the tension of said spring, release means adapted to be actuated to release said latch means, locking means adapted to prevent withdrawal of said drawer for a predetermined time, said locking means comprising a ratchet associated with said power spring and a solenoid-controlled pawl permitting rotation of said ratchet in one direction but not in the other, and means for releasing said solenoid and retracting said pawl.

6. In apparatus of the character set forth, a casing providing a drawer compartment, a drawer slidably mounted therein, a track running longitudinally of said compartment, a carriage on said track, means carried by said carriage adapted to engage said drawer to retract it when the carriage is retracted, a flexible strap member secured to said carriage and to a rotatably mounted drum, power means for rotating said drum, latch means for maintaining said carriage in forward position, release means adapted to be actuated to release said latch means, locking means adapted to prevent withdrawal of said drawer, and timing mechanism actuated when said carriage is retracted and after operation for a predetermined time adapted to release said locking means.

7. In apparatus of the character set forth, a casing providing a drawer compartment, a drawer slidably mounted therein, a carriage member provided with an interlock member adapted to engage said drawer to retract it when said carriage member is retracted, means slidably supporting said carriage member longitudinally of said compartment, releasable latch means for supporting said carriage member in the forward end of said

drawer compartment and out of engagement with said drawer, power means associated with said carriage for withdrawing said carriage toward the rear wall of said compartment, and locking means for preventing withdrawal of said drawer.

5

8. In apparatus of the character set forth, a casing providing a drawer compartment, a drawer slidably mounted therein, a carriage member mounted within said compartment for longitudinal movement therein, means associated with said carriage member for effecting the simultaneous retraction of said drawer with said carriage member, power means associated with said carriage for withdrawing said carriage and thereby said drawer, locking means confining the drawer in closed position, and release mechanism operating after a predetermined time to release said locking means.

9. In apparatus of the character set forth, a casing providing a drawer compartment, a drawer 20 slidably mounted therein, slidably mounted means within said compartment provided with an interlocking member adapted to engage said drawer to effect simultaneously the retraction of said drawer with said slidably mounted means, power 25 means associated therewith for withdrawing said slidably mounted means and thereby said drawer, and time-controlled locking means for preventing withdrawal of said drawer through a predetermined period.

30

10. In apparatus of the character set forth, a casing providing a drawer compartment, a drawer slidably mounted therein, guide means within said compartment, a slide member engaging said guide means and guided thereby for longitudinal 35 movement, interlocking means carried by said slide member normally not engaging said drawer but adapted to engage said drawer to effect its retraction when said slide member is retracted, power means associated with said slide member 40 for effecting its withdrawal, and locking means for preventing withdrawal of said drawer.

11. In combination: a casing; a drawer slidably mounted therein; extensible drawer-closing means rendered potentially operative by initially opening the drawer; a latch-device for holding said means in extended position, while the drawer is left free for closing and opening at will; and means for releasing said latch-device 50 to permit said drawer-closing means to function to automatically close the drawer.

12. In combination: a casing; a drawer slidably mounted therein; extensible drawer-closing means rendered potentially operative by initially opening the drawer; a latch-device for holding 55 said means in extended position, while the drawer is left free for closing and opening at will; and electrically controlled means for releasing said latch-device to permit said drawer-closing means to function to automatically close the drawer. 60

13. In combination: a casing; a drawer slidably mounted therein; extensible drawer-closing means rendered potentially operative by initially opening the drawer; a latch-device for holding said means in extended position, while the drawer is left free for closing and opening at will; means for releasing said latch-device to permit said drawer-closing means to function to automatically close the drawer; and a locking-device serving automatically to lock the drawer in closed 70 position.

14. A structure as specified in claim 11, in which said drawer-closing means comprises a slide adapted to actuate the drawer, a flexible 75

member for retracting said slide, and means for winding said flexible member to effect closing of the drawer.

15. In combination a casing, a drawer slidably mounted therein; extensible drawer-closing means rendered potentially operative by initially opening the drawer; a latch-device for holding said means in extended position, while the drawer is left free for closing and opening at will; electrically controlled means for releasing said latch-device to permit said drawer-closing means to function to automatically close the drawer; a locking-device serving automatically to lock the drawer in closed position; and means for preventing for a predetermined period unlocking of the drawer.

16. A structure as specified in claim 15, in combination with a locker beneath the drawer which has a door equipped with a lock subject to control

by the means which prevents unlocking of the drawer for a predetermined period, and means carried by the drawer for automatically dumping money or the like into the locker when the drawer moves to closed position.

17. In combination: a casing; a drawer slidably mounted therein; extensible drawer-closing means rendered potentially operative by initially opening the drawer; a latch-device for holding said means in extended position while the drawer 10 is left free for closing and opening at will; electrically controlled means for releasing said latch-device to permit said drawer-closing means to function to automatically close the drawer; and means for retarding the drawer-closing opera- 15

WILLIAM C. MILLER.
ALBERT L. ABBOTT.
